DOUBLE ACTING ELECTROHYDRAULIC OPERATOR

Filed Oct. 2, 1930

UNITED STATES PATENT OFFICE

1,970,517

DOUBLE ACTING ELECTROHYDRAULIC
OPERATORWilliam J. Woods, Schenectady, N. Y., assignor to
General Electric Company, a corporation of New
York

Application October 2, 1930, Serial No. 485,952

22 Claims. (Cl. 60—52)

My invention relates to electro-hydraulic operating devices, and provides an improved form of double acting or reversible electro-hydraulic operating device for producing a reciprocating motion which may readily be adapted for a wide field of service but is particularly advantageous for opening and closing elevator doors.

In the systems now generally provided for opening and closing elevator doors, use is made of pneumatically operated devices such as fluid operated cylinders or of electric motor driven lever mechanisms carried by the elevator cab proper and which engage the door to operate it. In the pneumatic systems making use of pistons and lever mechanism for opening and closing elevator doors it is necessary to provide some form of compressor usually located in the basement of the building in which the elevator system is installed. Conduits are led from the compressor system and tap off at the various floors to the pneumatic pistons and valves which control the lever mechanism for opening the doors. Such a system requires an elaborate layout and constant attention to maintain the system in operative condition. The control valves, the pistons and also the conduit leading the compressed fluid to the pistons are all subject to leaks which may cause a dangerous condition requiring suspension of the elevator service and expensive repairs.

In the second type of mechanism used for opening the doors the rotary motion of the electric driving motor must be converted into linear motion by means of elaborate and complicated ratchet and lever mechanism. Furthermore speed reduction gearing is necessary to reduce the speed of the driving motor so that it can be used for opening and closing the doors. Limit switches also are necessary to limit the movement of the doors and overload protective systems are required to insure safe operation. In the electric motor type of elevator door closing and opening apparatus the entire apparatus including the reduction gearing, limit switches, and overload devices are carried by the cab proper thus adding many hundreds of pounds to the weight of the cab besides occupying considerable space.

In both of the systems referred to some form of safety door check apparatus is necessary to prevent closing of the door with a slam. This safety door check mechanism is usually expensive and is subject to many of the same objections as the pneumatically operated mechanism for opening and closing the door.

It has been found that in both these systems

accidents occur by having passengers caught between the doors as the doors are closing. In both systems the pneumatically operated type and in the electric motor type when some object is caught between the doors the pressure exerted by the closing doors increases until the pneumatic system or the motor system becomes overloaded at which time some overload tripping device usually deenergizes the closing mechanism. However, before the tripping device operates serious injury may be done to the passenger.

Hence, it is one of the principal objects of my invention to provide a reversible electro-hydraulic operator for opening and closing elevator doors which is a self-contained unit of relatively small size and weight and of as simple and trouble-free construction as possible.

It is an object of my invention to provide an electro-hydraulic operator of the above type which eliminates the necessity for limit switches, overload protection, safety door checks, compressor apparatus and auxiliary pipes, and by means of which the safety of the passengers is assured.

It is a further object of my invention to provide an electro-hydraulic operator making use of a reversible electric motor together with a double impeller fluid pressure creating means and a reciprocating piston mechanism for imparting movement in opposite directions to a work engaging member.

Briefly, the preferred embodiment of my invention consists of a fluid casing provided with a central oil reservoir in which is mounted a double impeller reversible pump of unique structure, and having a pair of oppositely disposed cylinders connected to the central reservoir by communicating passages opening into the interior of the reservoir. The double impeller reversible pump is connected by means of a drive shaft to a reversible electric motor mounted upon the central reservoir. Slidably mounted upon an oil tube guide in each cylinder is a reciprocating piston, the two pistons being rigidly fastened together by means of a pair of connecting rods. These connecting rods are connected by means of a crank mechanism extending through the casing above the level of the oil within the reservoir to a pivotally mounted work engaging member operating outside of the casing. This form of crank connection eliminates the necessity for packing to prevent leakage of oil from the pistons if the connecting rods or other working parts extended through the casing below the oil level.

- Passageways are provided between the reservoir and the cylinders so that when the impeller pump is rotated in one direction or the other the pistons will move in response to the pressure created in the fluid in a direction corresponding to the direction of rotation of the double operating impeller pump. In this way selective operation of the work engaging member by a substantially constant fluid pressure or force in either direction may be obtained.
- 10 A more complete understanding of my invention will be obtained by reference to the accompanying drawing in which Fig. 1 shows a partial cross sectional view of a preferred form of my device; Fig. 2 a cross section taken through Fig. 1 as indicated by the sectional line A, A; Fig. 3 is a partial sectional view taken looking down upon the top of the device as shown in Fig. 1. Fig. 4 is a detailed showing of the clutch mechanism employed to effect selective actuation of the two impellers.

15 Referring specifically to the drawing, the fluid casing comprises the central reservoir 10 and the cylinders 11 and 12 fastened thereto at opposite sides thereof by means of suitable screws. The interior of the reservoir is filled with oil above the level of the cylinders as indicated by the dotted line in Fig. 1. The interior of the reservoir is provided with semi-circular portions 13 and 14 and with the chambers 43 and 44 in which the crank mechanism and members connecting the piston rods thereto may move.

20 Mounted in the bottom of the reservoir section of the casing is the impeller pump housing consisting of the portions 15, 15' and 16. The portions 13 and 14 are extended around to enclose the parts of the pump housing as shown at 13' and 14'. Rotatably mounted therein are the impellers 17 and 18 provided with the hub sections 17' and 18' to which the impeller blades are attached.

25 The mounting of the impellers upon the drive shaft 21 is shown in detail in Fig. 4. The impeller hubs 17' and 18' are provided with ratchet toothed indentations such as 17₁ and 18₁, which permit positive driving engagement in one direction only. Cooperating therewith are the clutching elements 27₁ and 27' provided with the toothed portions 28 and 28' which cooperate with the toothed indentations of the hubs; these elements being slidably keyed to the shaft 21 by means of the key 21' and urged into contact with the hub members by means of the spring 27. When the motor rotates the impeller shaft in one direction, let us say for example with a left-hand rotation, the clutching element 27₁ will engage one of the toothed indentations, such as 17₁, in the hub 17' and positively drive the same. Due to the inertia of the impeller hub 18' and the oil between the impeller blades and to the fact that the other clutching element can slip with respect to the toothed indentations in the hub 18' the clutching member 27' will merely slip over the teeth without rotating the impeller. When the rotation of the driving motor 22 is reversed the opposite action takes place, the impeller 18 being positively driven while the clutching member 27₁ will slip with respect to the impeller 17. The spring of course is so adjusted that the force exerted thereby upon the slipping clutching member is balanced by the force exerted by the inertia of the impeller and oil upon the clutching member to force it out of engagement with the impeller proper thereby permitting relative slipping between the drive shaft and the impeller.

30 The purpose of this construction is to permit a positive drive of each impeller in one direction only, the direction being opposite for each so that when the electric driving motor 22 is energized to rotate in either direction only one of the impellers will be rotated at a time. These impellers are driven by means of a drive shaft 21 connected between the impellers and the motor 22. Keyed to the shaft 21 is the fan 23 which tends to cool the motor and motor bearings during operation.

35 The pistons 29 and 30 are mounted within the cylinders 11 and 12 and slide on the oil tube guides 31 and 32 the pistons being rigidly fastened together by means of the connecting rods 35 and 36 so that during operation both pistons move together. The oil tube guides 31 and 32 are provided with the openings 33 and 34 respectively to permit the passage of oil to and from one side of the piston to the interior of the oil reservoir through the oil tubes and the openings 31' and 32' in the oil reservoir portion of the casing.

40 The housing for the impellers is provided with the exhaust openings 19 and 20 for connecting the interior of the cylinders 11 and 12 with the impeller pumps so that when the impeller 17 is energized oil will be forced through the opening 19 to one side of piston 29 in the cylinder 11 thus moving the pistons to the left, and similarly when the impeller pump 18 is energized oil will be forced through the passage 20 to the interior of the cylinder 12 to one side of piston 30 moving the pistons to the right.

45 Oil is introduced to both sides of the impellers during operation, at the top through the opening 26 in the impeller pump housing and at the bottom through the chamber 25 connected to the oil reservoir by chambers 43 and 44, and opening 25', the oil passing by the blades of the impeller which happens to be stationary during the operation of the other.

50 When oil is forced through the opening 19 into the cylinder 11 the piston 29 moves to the left and forces the oil on the left hand side thereof through the openings 33 of oil tube guide 31, 120 through the oil tube guide and the opening 31' to the interior of the reservoir 10. Similarly, when oil is forced through the passage 20 to one side of piston 30 oil will be forced from the right hand side of the piston 30 through the openings 34 125 and through the oil tube 32 to the interior of the oil reservoir through opening 32'.

55 The chamber 25 connects with the upper side of the impeller pump housing around the housing by means of the chambers 43 and 44 provided for the crank mechanism and which open up into the oil reservoir. This can be clearly seen in Fig. 2.

60 A work engaging member 42 is pivotally mounted on the outside of the casing and is connected to the connecting rods 35 and 36 by means of a crank mechanism consisting of the stub shafts 40₁ and 41, and crank arms 39 and 40 which are pivotally connected to the blocks 37 and 38 rigidly fastened to the connecting rods 35 and 36. 140 The crank members 39 and 40 are provided with elongated slots such as 39' (see Fig. 1) in order to permit free sliding and pivotal movement of the cranks during their reciprocating motion. Thus as the pistons move in opposite directions 145 the motion thereof is transmitted through crank mechanism to the work engaging member producing a reciprocating motion thereof.

65 The particular method employed in transmitting the motion of the pistons to the work engag- 150

ing member 42 by means of the stub shafts 40 and 41 mounted in bearings above the oil level is important. This eliminates the necessity for packings to prevent oil leakage, which packings are constantly a source of worry and trouble. Further, this particular crank connection results in a very compact unit, which could not be obtained by extending the connecting rods through the cylinders in line with the pistons.

- 40 The operation of the device is as follows: When the motor 22 is energized to rotate the impeller 18 by means of the spring urged clutching mechanism oil from the oil reservoir 10 reaches the top portion of the impeller through the opening 26 past the impeller 17 which is slipping with respect to drive shaft 21. Oil reaches the underside of the impeller from the oil reservoir 10 through the chambers 43 and 44 to the chamber 25 and through the opening 25. The oil is expelled therefrom through the passage 29 to the left-hand side of the piston 30 thereby causing a pressure to be exerted thereon to move the piston to the right. As it does so it forces the oil on the right-hand side thereof through the openings 34 of the oil tube guide 32, the oil tube 32 and back to the oil reservoir through the opening 32' in the oil reservoir 10. Piston 29 being connected to the piston 30 of course moves to the right with it and forces the oil on the right-hand side of the piston through the opening 19 to the top portion of the impeller 18 and to the reservoir proper. Oil reaches the left-hand side of the piston through the opening 31 in the oil reservoir, oil tube 31 and through the openings 33 therein.
- 45 A reverse action takes place when the motor 22 is reversed to positively drive the impeller 17, the oil entering the top portion and lower portion of the impeller 17 as described for the impeller 18. The tooth 28 is now forced into engagement with the teeth on the hub 17' to cause a positive drive, while the tooth which engages the hub 18' of the impeller 18 merely slips past the teeth without causing motion of the impeller. Oil is forced through opening 19 against piston 29 to move the pistons to the left. Of course, the motion of the pistons is transmitted through the crank mechanism to the work engaging member 42 and by intermittently reversing the motor 22 a reciprocating motion of the work engaging member may be obtained.

50 Since the motion of the pistons within the cylinders is slow enough for the purpose to be served no reduction gearing is necessary between the electric motor 22 and the impeller pump. No overload or limit switches are necessary in the construction given above because when the pistons reach either limit the impeller pump merely spins in the oil without causing any further movement of the work engaging member or overloading the motor. Since an electric driving motor is used electrical control is possible.

55 It will thus be seen that with my construction I obtain the ease of electrical control which is so highly desirable. By means of my unique construction I eliminate the necessity for using reduction gearing between the motor and the member to be operated on, the complicated gear and ratchet mechanism for obtaining linear motion from rotational movement, and limit and overload devices since these problems do not present themselves by the use of my construction.

60 The embodiment of the invention illustrated and described herein has been selected for the purpose of clearly setting forth the principles involved. It will be apparent, however, that the

invention is susceptible of being modified to meet the different conditions encountered in its use, and I, therefore, aim to cover by the appended claims all of the modifications within the true spirit and scope of my invention.

65 What I claim as new and desire to secure by Letters Patent of the United States, is:—

1. An electro-hydraulic operator including a fluid casing, a plurality of impeller pumps in said casing, for creating different fluid pressures in the fluid, a piston means movable in opposite directions in response to the different fluid pressures in the fluid in said casing, fluid connecting means between said pumps and piston means and electric driving means for selectively operating said pumps to cause movement of said piston means in opposite directions.

70 2. A hydraulic operator including a fluid casing, a pair of pistons immersed in the fluid therein, a pressure creating device in said casing comprising a pair of impeller pumps for moving said pistons, fluid connecting means between said pumps and said pistons, and driving means for selectively driving said pumps in opposite directions to create different pressures in said fluid 100 to move said pistons alternately in opposite directions.

75 3. An electro-hydraulic operator including an operating member movable each way between two positions, a reversible electric driving motor, and fluid pressure means operatively connecting the motor with the member and having a pressure creating impeller connected to be driven by the motor to effect operation of said member to one of said positions upon operation of the motor in one direction and a second pressure creating impeller connected to be driven by the motor to effect operation of said member to the other of said positions upon operation of the motor in the reverse direction.

80 4. A hydraulic operator including a fluid casing, a pair of oppositely disposed pistons mounted for simultaneous movement within the fluid in said casing, a pair of impeller pumps immersed in the fluid in said casing for creating a pressure to move said pistons, a reversible driving means therefor, and a selective clutch mechanism between said driving means and said pumps, said pumps being driven in opposite directions to produce a reciprocating movement of said pistons and a work engaging member operatively connected to said pistons to be moved thereby in response to the operation of said impeller pumps.

85 5. A hydraulic operator including a fluid casing comprising a central fluid reservoir and oppositely disposed fluid cylinders having connecting conduits to said reservoir, pistons mounted in said cylinders, and connecting rods rigidly connecting said pistons to each other to cause simultaneous movement thereof, a plurality of pressure creating impeller pumps each adapted to be driven in an opposite direction, a fluid connection between the discharge of each pump and one side of a different piston, a driving means for selectively operating said impellers whereby a pressure is alternately exerted upon each of said pistons to move the pistons alternately in opposite directions, and a work engaging lever mounted on the outside of said casing and means connecting said connecting rods and lever.

90 6. A hydraulic operator including a fluid casing, a pair of oppositely disposed pistons connected together and mounted for movement within the fluid in said casing, a pressure creating device comprising a pair of impeller pumps im-

mersed in the fluid for applying a pressure against said pistons, a driving means for selectively operating said pumps to move said pistons alternately in opposite directions, and a work engaging member operatively connected to said pistons whereby a reciprocating movement of said work engaging member is produced when said pumps are selectively operated.

7. A hydraulic operator including a fluid casing, a pair of oppositely disposed pistons mounted for movement within the fluid in said casing, means for rigidly connecting said pistons to each other to produce simultaneous movement thereof, a pressure creating device immersed in said fluid comprising a pair of pumps for selectively applying a pressure against said pistons to move the same alternately in opposite directions, a reversible driving means for said pressure creating device, connecting means between said driving means and said pumps for selectively operating said pumps, and a work engaging member operatively connected to said pistons whereby a reciprocating movement of said work engaging member is produced when said pressure creating means is selectively operated.

8. An electro-hydraulic operator including a fluid casing, a pair of pistons mounted for limited simultaneous movement within the casing, a pressure creating device for each of said pistons within said casing and a reversible electric motor for causing selective operation of said pressure creating devices for moving said pistons alternately in opposite directions, said pistons being balanced to remain at the limits of movement when the operating motor of said pressure creating means is deenergized.

9. An electro-hydraulic operator including a fluid casing, oppositely disposed pressure responsive means within said casing adapted to have a limited reciprocating movement in the fluid in said casing, a reversible pressure creating means in said casing comprising a pair of impeller pumps for alternately creating a pressure against said pressure responsive means for causing reciprocating movement of said pressure responsive means, and electric driving means therefor for selectively operating said pumps to cause said reciprocating movement, said pressure responsive means being balanced to remain at the limits of movement when said driving means is deenergized.

10. A hydraulic operator including a pair of cylinders, pistons in said cylinders connected to move together, a fluid reservoir, pressure creating means in said reservoir for moving said pistons and provided with intake and exhaust means, driving means for said pressure creating means, the exhaust means of said pressure creating means opening into the cylinders on one side of said pistons and conduits connecting the other side of said pistons and said reservoir, said conduits permitting a balance of pressure on opposite sides of said pistons when said driving means is deenergized.

11. A hydraulic operator including a pair of cylinders, pistons in said cylinders connected to move together, a fluid reservoir, pressure creating means in said reservoir for moving said pistons and provided with intake and exhaust means, driving means for said pressure creating means, the exhaust means of said pressure creating means opening into said cylinders on one side of said pistons and conduits extending through said pistons for connecting the other side of said pistons and said reservoir, said conduits permit-

ting a balance of pressure on opposite sides of said pistons when said driving means is deenergized.

12. A hydraulic operator for obtaining a reciprocating movement, including a fluid casing, said casing being provided with a fluid reservoir and oppositely disposed cylinders at right angles thereto, fluid tubes connecting said reservoir and the interior of said cylinders and providing passages thereto for fluid, pistons slideable on said tubes within said cylinders, rods rigidly connecting said pistons for causing simultaneous movement thereof, a pair of impeller pumps mounted in said casing, each impeller pump having an exhaust connected to one of said cylinders to create a fluid pressure therein to move the piston, driving means for said impellers, one only of said impellers being operative at a time whereby a reciprocating movement of said pistons may be obtained by alternate operation of said impellers, said tubes and exhausts providing passages for fluid to and from opposite sides of said pistons and a work engaging lever mounted upon the outside of said casing and operatively connected to said work engaging member.

13. A hydraulic operator including a fluid casing, a fluid therein, a pair of oppositely disposed pistons mounted within said casing for horizontal movement within the fluid, connecting rods rigidly connecting said pistons to cause simultaneously movement thereof, a pressure creating device immersed in the fluid intermediate said pistons for selectively operating said pistons to move them alternately in opposite directions, a driving means for said pressure creating means, a movable work engaging member mounted without said casing, blocks mounted upon said connecting rods for movement therewith, cranks pivotally connected to said blocks and extending through the casing above the level of the fluid therein, said work engaging member being connected to said cranks whereby upon movement of said pistons in response to operation of said pressure creating means a reciprocating movement of said work engaging member is obtained.

14. A hydraulic operator including a fluid casing, a pair of oppositely disposed pistons mounted for horizontal movement within the fluid in said casing, pumps immersed in the fluid for selectively applying a pressure to said pistons to move the same alternately in opposite directions, a driving means for selectively operating said pumps, connecting rods for connecting said pistons together to cause simultaneous movement thereof, blocks mounted upon said connecting rods for movement therewith, cranks slidably and pivotally connected to said blocks, bearings in said casing, stub shafts rotatably supported thereby, said cranks being connected to said stub shafts, a work engaging member mounted without said casing and keyed to said stub shafts whereby upon movement of said pistons alternately in opposite directions a reciprocating movement will be transmitted through said cranks and shafts to said work engaging member, said bearings for said stub shafts being mounted above the level of the fluid within said casing to prevent the leakage of fluid therefrom.

15. A hydraulic operator for obtaining a reciprocating movement including a fluid casing, pistons within said casing, connecting rods rigidly connecting said pistons for causing simultaneous movement thereof, means mounted in said casing for creating a fluid pressure in said casing to

- move said pistons, driving means for said pressure creating means, blocks mounted upon said connecting rods to move therewith, cranks slidably and pivotally connected to said blocks, bearings in said casing above the fluid level therein, stub shafts extending through said casing and rotatable in said bearings, a work engaging member mounted for movement with respect to said casing, said cranks and said work engaging member being operatively connected through said casing by means of said stub shafts, said block, crank and shaft connections between said connecting rods and said work engaging member transmitting movement of said pistons to said work engaging member when said pressure creating means is energized.
16. An electro-hydraulic operator for providing a reciprocating movement comprising a fluid reservoir, a pump housing and a pair of impeller pumps located therein for providing a fluid pressure, a plurality of cylinders disposed on opposite sides of said fluid reservoir, pistons slidably mounted therein and adapted to be operated by said pumps, connecting rods for connecting said pistons together to cause simultaneous movement thereof, passageways between said cylinders and said pump housing and said fluid reservoir and pump housing to permit the passage of fluid to and from said pumps when said pumps are operated to move said pistons, a reversible electric driving motor for rotating said impeller pumps, a spring actuated clutch mechanism between said impeller pumps and said electric driving motor for selectively rotating each impeller pump in an opposite direction upon reversal of said motor, whereby a reciprocating movement of said pistons will be obtained, and a work engaging member operatively connected to said pistons for transmitting said reciprocating movement.
17. An electro-hydraulic operator for providing a reciprocating movement including a casing having a central fluid reservoir and provided with cylinders oppositely disposed at right angles to said reservoir, fluid tube guides centrally disposed in said cylinders and provided with openings therein for providing a passage for fluid to and from the fluid reservoir and said cylinders, pistons slidably mounted on said tubes within said cylinders and rigidly connected together by connecting rods for causing simultaneous movement of said pistons, said tubes opening into said cylinders on one side of said pistons, a pump housing mounted in said fluid reservoir at the bottom thereof provided with intake and exhaust passages, said exhaust passage opening into said cylinders on the other side of said pistons, a pair of impeller pumps mounted for rotation within said housing for creating a pressure in said fluid for moving said pistons, electric driving means for said impellers, said driving means being adapted to have a selective operating engage-
- ment with said impeller pumps for rotating each pump in an opposite direction whereby a fluid pressure will be alternately created thereby on one side of each piston to move said pistons alternately in opposite directions, a work engaging lever mounted without said casing for pivotal movement and a crank mechanism extending through the casing above the level of the fluid for operatively connecting said pistons and said work engaging member for causing a reciprocating movement thereof.
18. An electro-hydraulic motor, comprising a double-acting hydraulic motor, a double acting reciprocating piston therein, rotary impeller pump means for supplying liquid under pressure for driving said double-acting piston, an electric motor driving said pump means, a rock-shaft for applying the force developed upon said piston, driving connections to said rock shaft from a part of said double-acting piston intermediate its ends, and a common housing for said pump means and double-acting piston, said rock shaft passing through said common housing above the liquid level in said housing.
19. An electro-hydraulic motor comprising a double-acting hydraulic motor having a double-acting cylinder and a double-acting piston therein, a pump incorporated with said hydraulic motor and located intermediate the ends of said double-acting cylinder, said pump comprising a rotary impeller for supplying liquid under pressure for driving said double-acting piston, and an electric motor driving said impeller, said electric motor having a shaft passing through said piston intermediate its ends and connected with said impeller.
20. An electro-hydraulic motor comprising a double-acting hydraulic motor having a double-acting cylinder and a double-acting piston therein, a pump incorporated with said hydraulic motor and located intermediate the ends of said double-acting cylinder, said pump comprising a rotary impeller for supplying liquid under pressure for driving said double-acting piston, said double-acting piston having a thrust-bar intermediate its ends, a rock-shaft for applying the force developed upon said piston, driving connections between said rock-shaft and thrust-bar, and an electric motor driving said impeller, said electric motor having a shaft passing through said piston intermediate its ends and connected with said impeller.
21. An electro-hydraulic motor according to claim 20, wherein said thrust-bar is divided, and said electric motor shaft passes through the divided parts of said thrust-bar.
22. An electro-hydraulic motor according to claim 20, wherein said thrust-bar is divided, wherein said rock-shaft is divided, and said electro-motor shaft passes through the divided parts of said thrust-bar and rock-shaft.

WILLIAM J. WOODS.
